UNITED STATES PATENT OFFICE.

FRANK McILVANE, OF DETROIT, MICHIGAN, ASSIGNOR TO DIAMOND POWER SPECIALTY COMPANY, OF DETROIT, MICHIGAN, A CORPORATION OF MICHIGAN.

BOILER-CLEANER.

1,245,750.

Specification of Letters Patent.

Patented Nov. 6, 1917.

Application filed June 10, 1916. Serial No. 102,833.

To all whom it may concern:

- Be it known that I, FRANK McILVANE, a citizen of the United States of America, residing at Detroit, in the county of Wayne 5 and State of Michigan, have invented certain new and useful Improvements in Boiler-Cleaners, of which the following is a specification, reference being had therein to the accompanying drawings.
- 10 The invention relates to boiler cleaners of the blower type, and refers more particularly to an improved construction adapted for use as a side unit.
- 15 Among the objects of the invention are to provide a side unit which can be adjustably actuated from the exterior of the furnace wall; to so arrange and mount the unit that the nozzles can be rotatably withdrawn to a position protected from the furnace heat
- 20 when not in use; to provide a mounting that will permit the nozzle header to be rotatably adjusted through an arc of approximately 180°; and to provide a frame box for the blower unit which both contains the blower
- 25 and forms a support in the setting wall.

The invention further resides in the simplified construction of the blower unit and its operating mechanism, and also in the arrangement whereby the work of installation and operation is materially reduced, and in such details of construction and arrangements and combinations of parts as will hereinafter appear.

In the drawings:

- 35 Figure 1 is a front elevational view of a blower unit embodying my invention;
- Fig. 2 is a side elevational view of the construction shown in Fig. 1;
- Fig. 3 is a top plan view thereof; and
- 40 Fig. 4 is a cross-sectional view of a modified construction of nozzle header.

In detail, A designates the furnace wall, having an opening B within which fits a frame-box C. The latter is preferably 45 formed of cast iron or other material sufficiently strong to support a part of the setting wall, as well as forming a housing for the blower unit D.

The blower unit comprises a nozzle header F provided with a plurality of nozzles G spaced to blow between the boiler tubes G'. This nozzle header is carried by a pipe E, which at its lower end is connected by a coupling H to a pipe I rotatably mounted in bearing supports J. The pipe I, in

turn, is connected by a swiveled pipe connection coupling L to a steam pipe M. The arrangement is such that the pipe E carrying the nozzle header F can be rotatably adjusted about the pipe I as an axis. This adjustment permits the nozzle header to be rotatably withdrawn into the frame-box and away from the furnace heat when not in use. When it is desired to clean the boiler tubes, it is only necessary to rock the pipe E and 65 the nozzle header F about its axis so as to successively direct the nozzles G against the various boiler tubes. Where the nozzle header is provided with a single row of nozzles, the lower wall of the frame-box C 70 is cut away, as shown at C', to permit the pipe E to be rocked about the axis I through an arc of approximately 180°, to the position shown in dotted lines in Fig. 2. Thus, upon the initial movement of the header the 75 nozzles G will discharge a jet of steam upwardly to clean the top portions of the boiler tubes, and will, upon its continued rotation, successively clean all portions of the boiler tubes G'. In place of rotating the 80 header and its supporting pipe E through so large an arc, the header may be supplied with an additional row of nozzles G², as shown in Fig. 4.

For manually operating the nozzle header 85 from the exterior of the furnace wall, I preferably provide the pipe E with a fitting N, to which is pivotally connected at O an operating rod P. The latter extends outward through the front wall Q of the frame 90 box, and at its end is provided with an operating handle R. At the point where the operating rod P passes through the wall of the frame-box, there is preferably an elongated slot S, so that the nozzle header can 95 be turned through the desired arc.

The invention, however, is not limited to the particular operating mechanism shown, nor to the details of construction except as specified in the appended claims.

What I claim as my invention is:—

1. In a boiler cleaner, the combination with a frame box adapted to be set in the furnace wall, said box having a plate substantially flush with the outer surface of 105 said wall, of a supply pipe extending into said frame box, a pipe having swivel connection with said supply pipe within said box, a header carried by the last mentioned pipe and extending parallel to the axis of 110

- swivel motion, and a member for actuating swivel motion extending from the swinging pipe through said plate at the front of the frame box.
- 5 2. In a boiler cleaner, the combination with a furnace wall, of a casing mounted in said wall, a steam pipe entering said casing, a pipe having swivel connection with said steam pipe at one end thereof, a jet header 10 mounted upon the other end of the last-mentioned pipe, said header being displaced through angular motion of said swivel pipe from a position within said casing to a position beneath the casing, and means for 15 manually actuating said motion.
3. In a boiler cleaner, the combination
- with a frame-box adapted to be set in the furnace wall, of a steam supply pipe extending into said box, an adjustable pipe having swivel connection within said box 20 and adjacent one of the walls thereof with said supply pipe, said wall having a cut-away portion to increase the arc through which the adjustable pipe may swing, a jet header carried by the free end of the adjustable pipe and displaceable by said pipe from a position within the frame-box to various positions exterior thereto, and means for swivelly displacing the adjustable pipe.
- 25 In testimony whereof I affix my signature. 30

FRANK McILVANE.
